UNITED STATES PATENT OFFICE.

OSCAR L. NOBLE, OF BOSTON, MASSACHUSETTS.

HEEL-TRIMMER.

SPECIFICATION forming part of Letters Patent No. 399,153, dated March 5, 1889.

Application filed March 13, 1886. Serial No. 195,163. (No model.)

To all whom it may concern:

Be it known that I, OSCAR L. NOBLE, of Boston, in the county of Suffolk and State of Massachusetts, have invented a new and useful Improvement in Heel-Trimmers, of which the following is a specification, reference being had to the accompanying drawing hereinafter referred to.

My invention is an improvement on a heel-trimming machine described in Letters Patent of the United States numbered 80,953, dated August 11, 1868.

The objects of my invention are, first, to provide the cutter with a loose collar that shall act as an anti-friction guard to protect the upper or counter of the shoe or boot while the heel is being trimmed, and also act as a guide to determine the form of the upper portion of the heel, thereby making the counter portion of the shoe and the upper portion of the heel nearest to the upper conform to each other; secondly, to provide a tread-guide and top-lift guard that will admit of trimming a heel that is straighter on the side and near the breast than it is at the rear, thereby adapting the machine for trimming heels that present different angles at each section from breast to rear without removing the corner of the top lift from the angle formed by the tread-guide and the guide or stop for the edge of the top lift.

My improved machine is illustrated in the accompanying drawing, which shows a tool embodying my invention.

It is obvious from the drawing that the side of the heel farthest from the cutter must be moved down in the direction of the dotted line $x\ x$, in order to trim the heel at all the varying angles formed by the surfaces of the tread and side of the heel as they successively occur from breast to rear of the heel.

A represents a part of the frame of the machine. The table or tread-guide is marked B, the arbor C, and the cutter D.

E is the guide for the edge of the top lift. The bushing F is slightly longer than the loose collar G, so that when the screw H is forced home the bushing F clamps the cutter D firmly in place and forms a journal to sup-

port and revolve within the loose collar G 50 when the shoe or boot is in contact with the collar G. The thread cut on A and B may be left off and the set-screw I may be used to fix the table or tread-guide B rigidly to A, or B may rest on a shoulder formed on A, as may 55 be found most convenient on different kinds of work. The operator places the corner of the top lift in the angle formed by B and E and the counter or upper of the shoe against the collar G, and then turns the boot or shoe 60 so as to bring every part of the sides of the heel in contact with the cutter D, and thus the shape of the top lift determines the form of the heel at and near the tread, and the counter of the shoe determines the shape of 65 that part of the heel near the upper.

With my improved machine a large class of heels (and the very great majority of modern heels are of that class) can be trimmed which could not be trimmed upon the machine 70 shown in Patent No. 80,953, while my improved machine is also well adapted for the old style of heels.

I am aware of Foster and Tolles's patent, No. 190,482, dated May 8, 1877, and Busell's patent, 75 No. 213,806, dated April 1, 1879, and disclaim all that is shown in them.

What I claim as my invention is—

1. The improved heel-trimming machine above described, consisting of table B, cutter 80 D, top-lift guide E, and collar G, the surface of the table being inclined to the axis of the cutter-arbor C, the table being recessed to receive the top-lift guide E, and the collar G being held by means substantially such as are 85 shown, substantially as described, and for the purpose set forth.

2. In a heel-trimming machine, the table B, with its surface inclined to the axis of the cutter, in combination with the cutter D and 90 the top-lift guide E, the table B being recessed to receive the top-lift guide, substantially as and for the purpose set forth.

OSCAR L. NOBLE.
